UNITED STATES PATENT OFFICE.

JOHN J. CATRON, OF BONHAM, TEXAS.

SAFETY-RAZOR.

1,394,886.

Specification of Letters Patent.

Patented Oct. 25, 1921.

Application filed April 13, 1920. Serial No. 373,681.

To all whom it may concern:

Be it known that I, JOHN J. CATRON, a citizen of the United States, residing at Bonham, in the county of Fannin and State of Texas, have invented certain new and useful Improvements in Safety-Razors, of which the following is a specification.

This invention relates to new and useful improvements in razors.

10 The invention has particularly to do with a razor having a longitudinally reciprocating blade arranged to be operated by the fingers of the person shaving with the razor. The particular result sought is simplicity, 15 compactness and efficiency in operation, together with certain other novel features which will be hereinafter more particularly pointed out.

In carrying out the invention a reciprocating blade carriage is mounted on a support which latter carries a guard. The blade is readily detachable from the carriage and acts as a means of preventing the disengagement of the carriage from the support until 25 the blade is removed. Such arrangement, however, is very satisfactory as by removing the blade the carriage may be removed from the support and the parts thoroughly cleansed. An operating member is provided 30 and connected with an actuating element which is connected with the carriage so that by manipulating the operating member the actuating element is placed in motion and the carriage reciprocated. Details of construction will be hereinafter more particularly pointed out.

The invention will be more readily understood from a reading of the following specification and by reference to the accompanying drawings, in which an example of the invention is shown, and wherein:

Figure 1 is an elevation of a razor constructed in accordance with this invention,

40 Fig. 2 is a side elevation of the device shown in Fig. 1,

Fig. 3 is a plan view of the carriage support or head of the razor,

Fig. 4 is a face view of the carriage,

Fig. 5 is a rear elevation of the carriage,

50 Fig. 6 is an enlarged plan view showing the carriage and a portion of the head, the blade being removed,

Fig. 7 is a plan view of the head and component parts with one of the blade retaining 55 wings in section,

Fig. 8 is a sectional detail of the handle and operating member, and

Fig. 9 is a cross sectional detail on the line 9—9 of Fig. 7.

In the drawings the numeral 10 designates a head or support which has an upstanding flange 11 at each end. Along its lower edge the head has a depending trough 12 the front edge of which is formed into a plurality of guard teeth 13. The trough is provided with longitudinal slots 14 having notches 15 in their upper sides as is clearly shown in Fig. 3. The head is fastened in a suitable manner to a curved shank 16, which is fitted into the end of a sleeve 17. The sleeve is fitted in the end of a handle member 18.

A blade carriage 19 is provided at each end with inturned overhanging wings 20. The carriage is bent longitudinally upon itself along its top edge to provide an apron 21 depending on the rear side of the carriage. A pair of ears 22 are upset from the upper portion of the carriage and bent downwardly between the base or body of the carriage and the apron. Along the lower edge of the carriage a pair of ears 23 are bent upward on the rear of said carriage. The carriage is engaged over the upper edge of the head 10 so that the apron hangs on the rear side of the edge and the upper ears 22 hang on the upper edge of the head. The lower ears 23 are positioned so as to pass through the notches 15, and thus when the carriage is moved to the left (Fig. 3) said carriage is fastened or held against displacement from the head and in order to remove the carriage it must be slid along so that the ears 23 may be lifted through the slots 15 as will be obvious.

A safety razor blade 24 is inserted in the carriage from the upper end of the latter so as to engage under the wings 20. The razor blade which is employed has laterally extending lugs 25 at its upper corners and the wings 20 are notched out at 20' so as to receive these lugs and thus limit the downward movement of the blade and also to control the proximity of its cutting edge to the teeth 13 of the guard. It will be noticed that the left hand flange 11 of the head (Figs. 3, 6 and 7) is provided with a projecting stop 11' and this stop is located in the path of the adjacent lug 25 of the razor blade and limits the reciprocation of the

carriage in that direction. By this means the carriage is stopped before the ears 23 register with the notches 15 as will be evidenced from Fig. 7, thus preventing the 5 disengagement of the carriage from the head until the blade 24 is removed. This is a very simple and convenient arrangement and permits the parts to be quickly disassembled by simply removing the blade 24.

10. A bell crank lever 26 is mounted on a pivot stud 27 seated in the shank 16. The lever has one end engaging in a notch 28 in the lower edge of the apron 21. The other end of the lever is pivoted to the forward end 15 of a link 29 which has its end pivoted in an eye 30 projecting from one side of a collar 31. The collar is concaved and fits on the sleeve 17 so as to slide freely. The sleeve 17 has a shoulder 17' which limits the inward or downward movement of the collar. It will be seen that by reciprocating the 20 collar the lever 26 is swung through the agency of the link, whereby the carriage 19 and its blade are reciprocated. For assisting in this operation the sleeve is provided with a slot 32 on each side and a transverse pin 33 fastened within the collar passes through this slot. A coiled spring 34 is confined between the pin and the bottom of the 25 sleeve. When the collar is pulled inward or toward its shoulder 17' the spring is compressed and thus assists in the outward movement of the collar.

In using the razor the operator grasps the 30 handle 18 and places the collar either between two of his fingers or between the index finger and his thumb. By pulling inward on the collar the blade and carriage are shifted to the right and by releasing the 35 collar, the spring which has been compressed returns the collar whereby the carriage and blade are swung or shifted to the left. By manipulating the collar rapidly the carriage and blade are operated or reciprocated with 40 sufficient rapidity to carry out a satisfactory cutting action. After the face has been 45 lathered the operator draws the razor down his face and uses the same in substantially the same manner as an ordinary safety 50 razor; the guard teeth 13 combing the beard and assisting in the shaving operation as will be obvious. After the razor has been 55 used it may be quickly taken apart by merely pulling out blade 24 and lifting off the carriage 19 as has been explained. The parts may be thoroughly cleansed and replaced. The trough 12 provides clearance under the cutting edge of the razor blade and also permits a free passage of the lather so that the 60 razor will not be clogged up. The slot 14 also facilitates the escape of the lather and cut hairs.

What I claim is:

1. In a razor, a support; a blade carriage

reciprocating on the support and removable 65 therefrom, a blade mounted in the carriage and movable therewith, means on the support and blade to retain the carriage on the support, a handle carrying the support, and an operating member carried by the handle 70 and having connection with the carriage for reciprocating the same.

2. In a razor, a head, a blade carriage reciprocating on the head and removable 75 therefrom, a blade mounted in the carriage to move therewith and serving to limit the longitudinal movement of the carriage in one direction, a handle carrying the head, a movable collar carried by the handle, an actuating element connected with the carriage, and a connection between the collar and the element.

3. In a razor, a head, a guard along one edge of the head, a blade carriage mounted to reciprocate on the head and having means 85 to retain the same upon the head when moved longitudinally within certain limits, blade retaining means on the carriage, a blade mounted on the carriage and held by the retaining means and engaging a portion 90 of the head to limit the longitudinal movement of the carriage in one direction, a shank extending from the head, a sleeve supporting the shank, a handle receiving the sleeve, a collar mounted to reciprocate on the sleeve, a bell crank lever mounted on the shank and engaging the carriage, and a connection between the collar and the bell crank lever.

4. In a razor, a head, a guard along one edge of the head, a blade carriage mounted to reciprocate on the head, a blade retaining means on the forward side of the carriage, a blade mounted on the forward side of the carriage and held by the retaining means, a 100 shank extending from the head, a sleeve supporting the shank, a handle receiving the sleeve, a collar mounted to reciprocate on the sleeve, a bell crank lever mounted on the shank and engaging the carriage, a connection 105 between the collar and the bell crank lever, and a coiled spring within the sleeve arranged to be compressed by the collar for assisting in the reciprocation of the collar.

5. In a safety razor, a head, having 110 notches, a carriage mounted to reciprocate on the head and having ears located to pass through the notches and engage the head whereby the carriage may be removed, a 115 razor blade fitting on the carriage and acting to prevent the registration of the ears of the carriage with the notches of the head until the blade has been removed, means for reciprocating the carriage, and a handle on which the reciprocating means is mounted. 120

In testimony whereof I affix my signature,

JOHN J. CATRON.
